[57] **CLAIM**

The ornamental design for a potato product, substantially as shown and described.

DESCRIPTION

FIG. 1 is a perspective view of a potato product embodying the new design;

FIG. 2 is a top plan view thereof;

FIG. 3 is a front end view thereof;

FIG. 4 is a left side elevational view thereof;

FIG. 5 is a rear end view thereof;

FIG. 6 is a right side elevational view thereof;

FIG. 7 is a bottom plan view thereof;

FIG. 8 is an enlarged sectional view taken along the line 8—8 FIG. 4;

FIG. 9 is a perspective view of a modified form of the potato product shown in FIG. 1;

FIG. 10 is a top plan view thereof;

FIG. 11 is a front end view thereof;

FIG. 12 is a left side elevational view thereof;

FIG. 13 is a rear end view thereof;

FIG. 14 is a right side elevational view thereof;

FIG. 15 is a bottom plan view thereof; and

FIG. 16 is an enlarged sectional view taken along line 16—16 of FIG. 12.
